UNITED STATES PATENT OFFICE

THOMAS B. SUMNER, OF EVERETT, WASHINGTON

SAWMILL HOG

Application filed January 27, 1930. Serial No. 423,736.

My invention relates to saw mill hogs and the like.

In the operation of the grinding machines commonly known as sawmill hogs, used in the grinding of waste lumber and refuse into hog fuel, small stones or pieces of gravel and tramp pieces of metal are frequently caught between the rotary grinding head and the anvil knives causing the knives to break and even the sudden stoppage of the rotary head, resulting in a heavy strain which tends to disrupt the entire machine.

This of course is costly in time and material, and in the manufacture of hog fuel, which being a waste product, must be converted as cheaply and economically as possible, is particularly objectionable.

Therefore, the object of my invention is to provide a sawmill hog provided with means adapted to quickly and automatically throw the knife elements of the hog out of action when an obstruction is caught between the knives, thereby to prevent the breaking of the knives or the said sudden stoppage of the machine, and also adapted to permit the hog to be quickly and easily put into operation again.

A further object of my invention is to provide such means adapted to permit the adjustment of the said knife elements relatively to each other, whereby they will be conveniently aligned for the grinding of hog fuel and the like.

The further object of my invention is to provide means comprising a stop and resilient element for limiting the reaction of said knife elements and absorbing the shock resulting from the sudden throwing of the hog out of action.

I attain these objects in a saw mill hog comprising a housing having a rotary cutter head journaled therein in combination with a movable, angular section carrying an anvil knife hingedly mounted in said housing on eccentric shaft sections, means for adjusting said shaft sections relatively to their eccentricity whereby the anvil knife will be aligned with said rotary cutter head, frangible means for holding said anvil knife in operative relation with said cutter head and

adapted to release said anvil knife under undue strain imposed on said knife elements, the housing provided with a portion constituting a stop for said hinged housing sections when released, a bumper element provided on said stop. 55

These and other incidental features of my invention, the details of construction, and mode of operation are hereinafter fully described with reference to the accompanying 60 drawings.

In the drawings:

Fig. 1 shows a longitudinal, vertical section taken on a central line of my hog and illustrates the relative arrangement of the 65 knife elements;

Fig. 2 shows a side elevation of the movable section carrying the anvil knife, removed from the machine;

Fig. 3 shows a section taken on the line 70 3—3 of Fig. 1;

Fig. 4 shows a side elevation of my hog and illustrates by broken lines the position taken by the movable section when my hog has been thrown out of action; 75

Fig. 5 shows an end elevation of my hog, taken looking in the direction of the arrow 5 in Fig. 1;

Figs. 6 and 7 show the details of the frangible elements when in service and after being broken by an undue strain; 80

Fig. 8 shows a section taken on the line 8—8 of Fig. 5 with parts broken away to show further details of construction;

Fig. 9 shows a side elevation of one of the 85 eccentric shaft sections removed from the machine;

Fig. 10 shows further details of the journal mountings for the said eccentric shaft sections; 90

Fig. 11 shows a section taken on the line 11—11 of Fig. 10.

Referring now to the figures, my saw mill hog comprises a housing *a* having a rotary cutter head journaled therein comprising inwardly converging frustro-conical sections *b*, *c*, fast on a driven shaft *d* journaled in the hog as at *f*. Transverse knives *g* are provided in the working faces of the said head in the usual manner. 95 100

The housing *a* is provided with a movable end section 2, right angular in longitudinal cross section, and hingedly mounted in the housing adjacent the corner formed by the two sides thereof on eccentric shaft section 3, hereinafter more fully described.

A V-shaped anvil knife 4 is secured to the inner face of the said movable section by bolts 5 in the usual manner for cooperation with the said rotary cutter head.

Cooperating flange portions 6 and 7 on the sides of the section 3 and housing *a* are provided with key hole slots 6*a*, 7*a*, respectively, in which are provided frangible bolts 8, adapted to hold the said movable section 2 and the anvil knife 4 in operative position with the rotary cutting head, under all conditions of normal services, see Figs. 1 and 8, but the said frangible bolts 8 are adapted to break under undue strain, as when, for instance, a piece of stone *x* or the like, which is too hard for the knife to work upon is caught between the knives, as illustrated in Fig. 1, in which case the movable section 2 will be caused to assume the position shown in broken lines in Fig. 4, and hence throw the said knives out of operative position.

To put the hog in operation again, it is only necessary to secure the section 2 in place and insert new frangible bolts in the said slots 7*a*, 8*a*, and the hog is again ready for service.

In order to insure that the anvil knife 4 will be properly aligned on its hinged axis with the said rotary cutter head, I have provided the before mentioned eccentric shaft sections 3, which consist of a flange head 10, concentric shoulders 11, and an intermediate eccentric bearing portion 12. The said shaft sections are journaled in downwardly projecting trunnions 13 on the movable section, and are supported in the base of the housing on the concentric shoulders 11 in the walls 14 of a cavity 15, provided therefor. The outer walls of the cavity are provided on their exterior surfaces with a number of concentrically arranged thread holes 16, and the flanged heads 10 of the shaft sections are provided with bolts 10*a* adapted to be threaded into the said holes 16.

By these means, the anvil knife 4 may be aligned and adjusted relatively to the rotary cutter head by rotating each of the shaft sections, and then securing them in position with the bolts 10*a*, which, due to the eccentric bearing portions 12, shifts the axis of rotation of the said section, and hence moves the anvil knife relatively to the cutter head.

In order to provide a stop element for the section 2, when it is thrown out of action, the walls of the adjacent base portion *a'* of the housing are formed so as to slope downwardly away from the cavity 15, thus leaving the lower portion of the section 2 unsupported when in operative positions, and resilient bumpers 18 are provided thereon, against

which the side flanges 2*b* on the said lower portion of the movable section 2, are adapted to strike, when the said frangible bolts are broken by undue strain, and the said movable section is caused to assume the position shown by broken lines in Fig. 1.

I claim:

1. In a saw mill hog, the combination of a housing having a rotary cutter head journaled therein, a movable section carrying an anvil knife hingedly mounted in said housing on eccentric journal bearings, means for rotating said journal bearings whereby the anvil knife will be shifted relatively to said rotary cutter head and aligned with the latter, means for holding said anvil knife in operative relation with said cutter head and adapted to release said anvil knife under undue strain imposed on said knife elements.

2. In a saw mill hog, the combination of a housing having a rotary cutter head journaled therein, a movable section carrying an anvil knife hingedly mounted in said housing on eccentric shaft sections, means for rotating said shaft sections whereby the anvil knife will be shifted relatively to said rotary cutter head and aligned with the latter, means for holding said anvil knife in operative relation with said cutter head and adapted to release said anvil knife under undue strain imposed on said knife elements.

3. In a saw mill hog, the combination of a housing having a rotary cutter head journaled therein, a movable, angular section carrying an anvil knife hingedly mounted in said housing on eccentric shaft sections, means for rotating said shaft sections whereby the anvil knife will be shifted relatively to said rotary cutter head and aligned with the latter, frangible means for holding said anvil knife in operative relation with said cutter head and adapted to release said anvil knife under undue strain imposed on said knife elements.

4. In a saw mill hog, the combination of a housing having a rotary cutter head journaled therein, a movable, angular section carrying an anvil knife hingedly mounted in said housing on eccentric shaft sections, means for rotating said shaft sections whereby the anvil knife will be shifted relatively to said rotary cutter head and aligned with the latter, frangible means for holding said anvil knife in operative relation with said cutter head and adapted to release said anvil knife under undue strain imposed on said knife elements, the housing provided with a portion constituting a stop for said hinged housing sections when released, a bumper element provided on said stop.

5. In a saw mill hog, the combination of a housing having a rotary cutter head journaled therein, a movable section carrying an anvil knife hingedly mounted in said housing on eccentric journal bearings, means for

rotating said journal bearings whereby the anvil knife will be shifted relatively to said rotary cutter head and aligned with the latter, means for holding said anvil knife in operative relation with said cutter head and adapted to release said anvil knife under undue strain imposed on said knife elements, the housing provided with a portion constituting a stop for said hinged housing sections when released.

6. In a saw mill hog, the combination of a housing, a rotary cutter-head journaled therein, a hinged housing section carrying an anvil knife, the axis of the hinge being located at the interior lower corner of said hinged section, and said hinge including adjustable means for adjusting the anvil knife relatively to the cutter-head, the opposed faces of said section and the housing when in abutment adapted to position the anvil knife in operative relation with the cutter-head, means for holding said movable section in operative position under normal strain but adapted to break under abnormal strain, the housing provided with a supporting surface adapted to support said hinged section, when released, with the anvil knife inoperatively spaced from said cutter-head.
